UNITED STATES PATENT OFFICE.

JOHN B. GOODWIN, OF BALTIMORE, MARYLAND, ASSIGNOR TO THE SOVEREIGN GRAND LODGE OF THE INDEPENDENT ORDER OF ODD FELLOWS, A CORPORATION OF MARYLAND.

DESIGN FOR AN OFFICIAL CERTIFICATE.

42,128.

Specification for Design.

Patented Feb. 6, 1912.

Application filed November 16, 1911. Serial No. 660,725. Term of patent 14 years.

To all whom it may concern:

Be it known that I, JOHN B. GOODWIN, a citizen of the United States, residing at the city of Baltimore, in the State of Maryland, have invented a new, original, and ornamental Design for an Official Certificate, of which the following is a specification, reference being had to the accompanying drawing, forming part thereof.

Figure 1 is the front view of an official certificate, showing my new design. Fig. 2 is the rear view of an official certificate, showing my new design.

I claim:—

The ornamental design for an official certificate, as shown.

JOHN B. GOODWIN.

Witnesses:

J. ALEX. HILLEARY, Jr.,
FRED. A. GROOM.
